WINDING MACHINE

Robert J. Bartholomew, Germantown, Pa.

Application July 10, 1936, Serial No. 90,030

5 Claims. (Cl. 242—2)

My invention relates to an improvement in winders, and particularly a winder designed to form yarn or thread into a ball or coil.

An object of my invention is to provide mechanism of this type which is simple in construction, inexpensive to produce, made up of a small number of parts assembled so that the device can be readily and quickly mounted, and which can always be easily operated to perform with 10 smoothness and certainty the function required.

A further object is to provide a ball winder that is compact, strong and durable, with the various members thereof so arranged that the device is very satisfactory to handle, and which 15 is virtually incapable of getting out of order.

Other objects and advantages of the invention are set forth in the ensuing description, and the novel features are defined in the appended claims. But this disclosure is explanatory only, 20 and various changes in details may be adopted without going beyond the principle of the invention or exceeding its scope.

A preferred embodiment of my invention is illustrated on the accompanying drawing in 25 which:—

Figure 1 is a side view of a winder according to my invention, partly in section, and

Figure 2 is a front view of a detail.

The drawing shows a support 1 adapted to be 30 secured in upright position and carrying at its upper extremity a bearing 2 which receives the rotatable shaft 3. Fixed to one end of shaft 3 is a handwheel-crank 4, the object of which is to turn said shaft, and fixed to the other end of 35 shaft 3 is an arm 5. This arm bears at its outer extremity the stud or pin 7, preferably riveted in said arm and serving as a journal for the dished gear 10. This pin passes loosely through the hub 12 of said gear, which can 40 therefore rotate about the pin freely. The hub 6 of the arm 5 is made fast to the spindle 3 in any feasible way, and integral with said arm 45 adjacent to the hub is a shield or hood 8 that surrounds a gear 9 on the bearing 2. The gear 9 has a hub 13 which telescopes over the adjacent end of the bearing 2; and this gear is thereby made fast to the bearing and is motionless thereon. The shield at one point has an opening 11 which permits the gear 10 at all times 50 to be in mesh with the gear 9. The purpose of this hood 8 is to prevent any accidental contact of the teeth of the gear 9 and the person of the operator or the clothing of the latter.

The hub 12 of the dished gear 10 also serves to 55 mount the winding spindle 14 on which the

thread is wound. This spindle or bobbin 14 is hollow and one end is pushed upon the hub, 12, which fits snugly therein. If desired, a spool (not shown) to receive the thread may be slipped on the bobbin and held motionless thereon 5 through frictional contact. The parts are so disposed that the longitudinal axis of the winding spindle 14 intersects the axis of shaft 3 at a point 17 directly above eyelet guide 15. In other words, a line drawn vertically through 10 the center of guide 15 to the axis of winding spindle 14 will meet this axis at the point 17 where this axis intersects the axis of the shaft 3.

Since the gear 9 is fixed in position and is meshed with gear 10, any revolution of the handwheel-crank 4 will not only cause a revolution of the arm 5 (including its connected parts 7, 10, 12, and 14) about the axis of shaft 3 but will also result in a separate rotation of gear 10 and winding spindle 14 about their own common axis. 15 This latter motion is plainly due to the fact that on rotation of lever arm 5 the teeth of fixed pinion 9 tend to hold back the gear 10 and so cause the gear 10 to rotate about its own 20 axis in the same direction as the handwheel-crank 4. 25

The resultant motion then of the winding spindle 14 is seen to be a combination of two separate rotations—rotation about its own axis and revolution about the axis of shaft 3—describing in space a pair of circular cones each 30 having its apex located at the point 17.

In practice the thread to be wound is led from a reel or swift (not shown) through the guide aperture 15 and made fast to the winding spindle 35 14, by insertion in a slit therein for example, or by taking a few turns about the winding spindle 14, or a spool thereon. Then upon rotation of the handwheel 4, the motions of the various parts hereinbefore described operate to build 40 up a ball of thread; indicated in outline at 16, the turns of the thread continually crossing one another.

When the ball is complete it will slide easily off the spindle 14 when seized by hand and the 45 thread can be pulled out from the interior or exterior of the ball and used for knitting, darning, and other purposes.

The winder is intended to be used to a large extent by women who buy wool in skeins or hanks, 50 and then wish to roll it up into smaller compass. By my invention this step is greatly facilitated.

The lower end of the support 1 has two jaws 18 to enable it to be easily clamped to a table or the like. One jaw, such as the lower, bears a clamp 55

screw 19 with a head to hold the winder securely when it is in operation. The guide 15, as illustrated herein, may be an extension of the upper jaw.

5. To prevent displacement of the hub 12 and gear 10 the pin 7 may be enlarged as at 20.

It is further to be observed that, although the hood 8 is disposed over the gear 9 and adjacent the end of the shaft 3, the arm 5 lies between the gears 9 and 10 and the support 1. By this arrangement the winder is rendered more compact and the distance from the center of the gear 10 to the outer extremity of the spindle 14 is as short as possible.

15. It will be observed that the handwheel-crank is at one end of the shaft 3; and the arm 5, the opening 11 in which is fully illustrated in Figure 2, is affixed to the opposite end of said shaft. In a device of this kind, there is no way of varying the 20 distance from one thread on the spindle 14 to the next; therefore the gear ratio must lie within close limits to produce a satisfactory ball. In practice the relative diameters of the "sun" gear 9 and the "planet" gear 10 should be as 100 is to 2502 or 308, or as 100 is to 292 or 298. A smooth and compactly wound ball can then be obtained.

What I claim is:

1. A ball winder comprising a support having clamp jaws thereon, one of said jaws having a 30 fastening bolt and the other a guide aperture, a bearing on the support, a shaft in the bearing, an arm secured to the shaft, a journal on said arm, a gear on said journal, a bobbin affixed to said gear, a gear fixed non-rotatably to the bearing, 35 the arm having one end shaped to form a hood for the fixed gear and the adjacent end of the shaft and bearing, and the rest of the arm lying between a portion of the support and the first-named gear, the arm having an aperture adjacent the hood to enable the gears to be in constant engagement with each other.

2. A ball winder comprising a support having clamp jaws thereon, one of said jaws having a fastening bolt and the other a guide aperture, a 40 bearing on the support, a shaft in the bearing, an arm secured to the shaft, a journal on said

arm, a gear on the journal, said gear having a hub, a bobbin mounted on said hub, a gear fixed non-rotatably to the bearing, the arm having one end formed to provide a hood for the fixed gear and the adjacent end of the shaft and bearing, the remainder of the arm being disposed between a portion of the support and the first-named gear, the arm having an aperture adjacent the hood to permit constant engagement of said gears with each other. 10

3. A ball winder comprising a support, a bearing on the support, a shaft in the bearing, an arm secured to the shaft, a journal on said arm, a gear on said journal, a bobbin affixed to said gear, a gear fixed non-rotatably to the bearing, 15 the arm having one end shaped to form a hood for the fixed gear and the adjacent end of the shaft and bearing, and the rest of the arm lying between a portion of the support and the first-named gear, the arm having an aperture adjacent the hood to enable the gears to be in constant engagement with each other.

4. A ball winder comprising a support, a bearing on the support, a shaft in the bearing, an arm secured to the shaft, a journal on said arm, a 20 gear on the journal, said gear having a hub, a bobbin mounted on said hub, a gear fixed non-rotatably to the bearing, the arm having one end formed to provide a hood for the fixed gear and the adjacent end of the shaft and bearing, the remainder of the arm being disposed between a portion of the support and the first-named gear, the arm having an aperture adjacent the hood to permit constant engagement of said gears with each other. 25

5. A ball winder comprising a support, a bearing on the support, a shaft in the bearing, a non-rotatable gear fixed to the bearing, an arm secured to the shaft, a rotatable gear adapted to engage with said non-rotatable gear and a bobbin supported by said non-rotatable gear mounted on the free end of said arm, and a hood carried by said arm and extending partially around the fixed gear and the adjacent end of the shaft and bearing. 30 35
